METHOD OF AND MACHINE FOR USE IN
THE MANUFACTURE OF SHOESLester S. Macdonald, Beverly, Mass., assignor to
United Shoe Machinery Corporation, Paterson,
N. J., a corporation of New Jersey

Application March 20, 1933, Serial No. 661,644

41 Claims. (Cl. 12—10)

This invention relates to the manufacture of shoes and, in some of its aspects, more particularly to the manufacture of shoes of a kind in which the upper is secured in lasted relation to an insole by adhesion.

Objects of the present invention are to provide an improved method of making shoes and also a machine adapted for use in the practice of the method. In the attainment of one of its objects 10 the invention provides a novel method of making shoes in which cement is used as an upper-securing medium, in the practice of which different portions of the upper are fastened in lasted relation to a last and to an insole on the last by 15 fastenings which are themselves adhesively secured to the upper and the insole to hold the upper in lasted position until the cement has set and are thereafter removed from the shoe. The fastenings, as illustrated herein, comprise strips 20 of adhesive material which are laid over the margin of the upper and against the bottom face of the insole in the lasting operation, the material being of such a character as to adhere quickly and firmly to the upper and the insole. In the illustrated manner of practicing the method the temporary fastenings are removed from the shoe, after the cement has set, during and as an incident to an upper-roughening operation whereby 25 the overlaid margin of the upper is roughened to 30 prepare it for the reception of an adhesive for attaching an outsole to the shoe. In another aspect, the invention provides a novel method of lasting, whereby adhesive fastenings are applied progressively to the shoe in the laying of the marginal portion of the upper over the insole.

For use in lasting shoes in the practice of the novel method there is provided, in accordance with one feature of the invention, a novel organization comprising means for pulling an upper over 40 a last and means for laying the margin of the upper over an insole on the last and fastening it in lasted position by fastenings which are adhesively secured to the upper and the insole. As herein illustrated, there is a gripper for pulling the upper over the last and an overlaying member for laying the margin of the tensioned upper over the insole and for also pressing a fastening of adhesive material into position to adhere to the upper and the insole. In the construction shown, 45 the overlaying member comprises a freely rotatable roll which is moved inwardly over the shoe bottom by a carrier and is arranged to engage the end of an adhesive tape and as it moves inwardly to feed a portion of the tape from a source of 50 supply and lay it over the upper and against the 55

insole, a tape-controlling member being provided on the carrier to cooperate with the overlaying roll to bend the adhesive tape around the roll so as to position the end of the tape beneath the roll.

As herein shown, the above-mentioned carrier is mounted for forward movement in a direction inclined toward the bottom of the shoe and, in order that the margin of the upper will be pressed into firm adhering relation to the insole throughout the entire width of the margin, there is provided, in accordance with a further feature of the invention, means for imparting to the overlaying member substantially at the beginning of the forward movement of the carrier a movement in a different direction to carry it into position to press the margin of the upper initially against the outer edge portion of the bottom face of the insole, and for then controlling the movement of the overlaying member inwardly of the shoe bottom in such manner as to cause it to move in a plane substantially parallel to the bottom surface of the last. Thereafter the overlaying member is moved upwardly away from the shoe bottom in a direction substantially at right angles to the direction of its inward movement. Thus, as herein illustrated, the movements of the overlaying and fastening-applying member are so controlled that as it moves inwardly over the shoe bottom it presses the margin of the upper for its entire 30 width against the insole and lays a fastening from the edge of the shoe bottom inwardly over the margin of the upper and against the insole beyond the inner edge of the upper. It is to be understood, however, that with respect to the 35 above-described movements of the overlaying member the invention is not limited to an organization in which an adhesive fastening is applied to the shoe by this member.

For severing the adhesive fastenings from their 40 source of supply there is provided, in accordance with another feature of the invention, means operating in time relation to the movements of the overlaying and fastening-applying member for severing that portion of the adhesive material 45 which has been laid over the margin of the upper and against the bottom face of the insole. As illustrated, a knife is provided which is mounted for movement in the above-mentioned carrier beneath the fastening-applying member. The 50 knife is operated by a spring which is arranged to be tensioned by movement of the fastening-applying member toward the work and which is released to render it operative after the member 55 has completed its movement inwardly over the

shoe bottom and substantially at the time when the member begins its movement upwardly away from the shoe bottom. The fastenings are thus severed from their source of supply close to the bottom face of the insole after they have been pressed into position to adhere to the upper and the insole in the lasting operation.

The above and other features of the invention, including various novel details of construction and combinations of parts, and also the novel method aspects of the invention, will now be more particularly set forth by reference to the accompanying drawings and pointed out in the claims.

In the drawings,

15 Fig. 1 is a view in side elevation of a portion of a machine adapted for use in the practice of the method and in which features of the invention are embodied, illustrating the positions of the parts when the machine is at rest;

20 Fig. 2 is a view of a portion of the structure shown in Fig. 1, but illustrating the positions of the parts substantially at the beginning of the inward movement of the overlaying and fastening-applying member;

25 Fig. 3 is a view similar to Fig. 2, but illustrating the positions of the parts substantially at the completion of the inward movement of the overlaying and fastening-applying member;

30 Fig. 4 is a view similar to Fig. 2, but illustrating the positions of the parts substantially at the beginning of the movement of the overlaying member upwardly away from the shoe bottom;

35 Fig. 5 is a view in front elevation of parts shown in Fig. 1;

40 Fig. 6 shows a shoe as it appears after the upper along the sides of the shoe has been lasted in accordance with the method of this invention and by the illustrated machine; and

45 Fig. 7 is a perspective view of the shoe as it appears during the step of roughening the overlaid margin of the upper and removing the temporary fastenings.

50 The machine illustrated herein is of the same general type as the machine fully shown and described in Letters Patent of the United States No. 1,796,451, granted March 17, 1931 on an application of George Goddu. Accordingly, it is only necessary to refer herein, for the most part, to the construction and the mode of operation of the novel overlaying and fastening-applying mechanism of this invention.

55 It will be understood that the shoe upper materials 29, hereinafter frequently referred to inclusively as the shoe upper and including, for example, the upper leather *a* and the lining *b*, and the insole 22 are assembled on the last 24 and the upper pulled over in the usual manner prior to the side-lasting operation. Before performing the side-lasting operation by the use of the illustrated machine, the margins of the various layers of the shoe upper materials (with the exception of the outer face of the upper leather) from a point substantially at or somewhat to the rear of the heel breast line to substantially the tip line 60 may be coated with an adhesive which may or may not also be applied to the margin of the insole. The shoe is then supported bottom upward in the hands of the operator and adjacent portions of the sides of the shoe presented successively to the lasting instrumentalities of the machine.

65 In each lasting position of the shoe the upper materials are pulled by a gripper 26 and are then laid inwardly over the insole 22 and pressed into position to adhere thereto and are fastened initially in lasted position by temporary non-me-

tallic fastenings. The temporary fastenings, as herein shown, comprise strips of adhesive material having one side only prepared with an adhesive which is sufficiently tacky to permit the strips to be adhesively secured to the overlaid margin of the upper and to the bottom face of the insole in the lasting operation. The present invention contemplates allowing the fastenings to remain on the shoe bottom until the cement has set sufficiently to retain the upper in lasted position and then removing them, although this procedure may be varied if an outsole is to be attached permanently to the upper by stitches, in which case the fastenings may remain in the shoe. In such a case also the use of adhesive between the upper materials and the insole may be dispensed with.

70 To assist in determining the proper relation of the shoe to the lasting instrumentalities of the machine there is provided an edge gage 28 which is arranged to engage the side of the shoe at or near the edge of the insole and a sole rest 30 arranged to engage the shoe bottom at a considerable distance from the edge of the shoe bottom. The edge gage 28 is pivotally mounted at 32 on a bracket 34 which is adjustable along a guideway 36 formed in the head of the machine and is held in adjusted position by a cap screw 38.

75 The gripper 26 comprises a pair of jaws 40 which, in the illustrated machine, are curved laterally to permit their upper-gripping portions to be offset lengthwise of the edge of the shoe bottom relatively to other portions of the gripper to provide room for the operation of the novel overlaying and fastening-applying mechanism of this invention. The means for operating the gripper is not shown or described herein since it is the same as similar means shown and described in the prior Letters Patent hereinbefore mentioned. As more fully described in that patent the gripper 26 is moved first downwardly toward the bottom surface of the shoe and then outwardly into position to grip the shoe upper materials, after which it is given a heightwise movement to tension the upper over the last and then a movement inwardly over the shoe bottom while maintaining its hold on the upper. As the gripper 26 completes its inward pulling movement the lasting margin of the upper adjacent to the gripper is laid over the margin of the insole and pressed into position to adhere thereto by means which is arranged also to lay a strip of adhesive material over the margin of the upper and against the bottom face of the insole to hold the upper in lasted position. In order that the margin of the upper will be 80 pressed into position to adhere firmly to the insole throughout the entire width of said margin the overlaying means is moved into position to press the margin of the upper against the outer edge portion of the bottom face of the insole substantially at the beginning of its overlaying movement and preferably this movement of the overlaying member into pressure-applying position is completed before the gripper releases its hold on the upper.

85 In the illustrated machine the means for laying the margin of the upper over the insole comprises a freely rotatable roll 42 mounted on a laterally extending pin 44 in a cap 46 secured to the lower end of a bracket 48. The bracket 48 is secured to the forward end of a carrier or slide 50 which is mounted for movement in a forwardly and downwardly inclined guideway formed on a member 52. The member 52 is secured by screws 54 to a holder 56 which has a downwardly extending 90

portion fast on a rock shaft 60 mounted in the head 62 of the machine. The slide 50 is moved along the guideway toward and from the shoe by a cam 64 which engages a roll 66 on the slide and which is formed in one side of a cam wheel 68 fast to a cam shaft 70 in the head of the machine.

As previously pointed out, the overlaying member is moved into position to press the margin of the upper adjacent to the edge of the shoe bottom against the insole substantially at the beginning of its overlaying movement. For this purpose there is secured to the rock shaft 60 a lever 72 provided with a roll 74 engaged by a power cam 76 formed in one side of a cam wheel 77 on the shaft 70. The configuration of the cam 76 is such that as the slide 50 begins its forward movement the member 56 that supports the slide is swung in a clockwise direction as viewed in Fig. 1 to impart to the overlaying member 42 a movement in a different direction to carry it into position to press the margin of the upper against the margin of the insole adjacent to its outer edge. As the slide 50 continues its forward movement the cam 76 acts to swing the member 56 about its pivot in a counterclockwise direction to vary the direction of movement of the slide 50 in such manner as to cause the overlaying member 42 to be moved inwardly over the shoe bottom in a plane substantially parallel to the bottom surface of the last to lay the margin of the upper over the insole. After the slide 50 has completed its forward movement, a further swinging movement in a counterclockwise direction is imparted to the member 56 to carry the overlaying member 42 upwardly away from the shoe bottom in a direction substantially at right angles to the direction of its inward movement, after which the slide 50 is retracted to return the member 42 to its initial position.

In the illustrated machine the overlaying member 42 serves also as a member for applying fastenings to the upper and the insole to hold the upper in lasted position. The fastenings as herein illustrated comprise strips 75 of adhesive material or tape which are fed from a source of supply and pressed into position to adhere to the margin of the upper and the bottom face of the insole as the overlaying member moves inwardly over the shoe bottom to press the margin of the upper against the insole. As shown in Fig. 1, there is loosely mounted on a support or spindle 78 on the bracket 48 a roll 80 of adhesive tape, a portion of which extends downwardly over a guide roll 82 pivotally mounted in the bracket 48 above the overlaying member 42 and into engagement with the overlaying member. As shown, the end of the tape is engaged by a tape-positioning member 84 which is adjustable toward or from the overlaying member 42 in a downwardly and rearwardly extending guideway 86 formed in the bracket 48, a cap screw 88 being provided for holding the member 84 in adjusted position.

The tape-positioning member 84 is provided with an end 90 which, as shown, is formed and arranged to cooperate with the overlaying member 42 to bend the end of the adhesive tape beneath the overlaying member and thus to hold the end of the tape in position to be engaged by the overlaying member and pressed against the margin of the upper as the overlaying member moves into position to press the margin of the upper against the outer edge of the shoe bottom. It will be readily seen that as the overlaying member is moved downwardly into position to

press the margin of the upper against the insole substantially at the beginning of its overlaying movement the end of the adhesive tape will be engaged by it and pressed into position to adhere to the margin of the upper, and that as the overlaying member moves inwardly over the shoe bottom a portion of the tape will be fed from the roll 80 and laid over the margin of the upper by the movement of the member. In order that the tape will be adhesively secured also to the adjacent portion of the bottom face of the insole the cam 64 is so formed that a forward movement of sufficient extent is imparted to the slide 50 to carry the overlaying member inwardly over the bottom face of the insole.

For holding the roll 80 of adhesive tape on its support there is provided a cover 92 which is pivotally mounted at 94 on the bracket 48 and is held in engagement with a finished surface 96 (Fig. 5) on the bracket by means of a spring 98. The cover 92 is provided with a handle 100 by means of which it may be swung about its pivot 94 to facilitate removal and replacement of the rolls of adhesive tape.

For severing from the roll of adhesive tape that portion of it which has been applied to the upper and the insole by the overlaying member there is provided means operating in time relation to the movements of the overlaying member for cutting the tape close to the bottom face of the insole substantially at the time when the overlaying member begins its movement upwardly away from the shoe bottom. As shown particularly in Fig. 1 the cap 46 is provided with a guideway 102 for a chopping knife 104 which is carried by a member 106 pivotally connected to the lower end of an arm 108 which at its upper end is pivoted on a stud 110, Fig. 5, carried by the slide 50. The knife 104 is held in adjusted position relatively to the member 106 by means of a cap screw 112 and preferably is so adjusted, when the parts are in their idle positions, that its cutting edge extends beyond the axis of the pin 44 a distance slightly greater than the radius of the roll 42 plus the thickness of the adhesive tape. The arm 108 is operated to impart tape cutting movement to the knife 104 by a torsion spring 114, Figs. 1 and 5, one end of which is connected to a member 116 which may be turned to adjust the tension of the spring and is held in adjusted position by a pin 118 arranged to enter any one of a series of holes 120 formed in a member 122 fast on the end of the stud 110. To limit the driving movement of the arm 108 there is provided a fiber washer 124 which is adjustable by means of a screw 126 mounted in a split bracket 128 on the slide 50, a screw 130 being provided for effecting relative movement of the two parts of the split bracket to bind the screw 126 in adjusted position.

For swinging the arm 108 against the resistance of the spring 114 to retract the knife 104 preparatory to the tape-cutting operation there is pivoted at 132 on the head of the machine a lever 134, Fig. 1, on which is pivotally mounted at 136 a latch 138 for engaging the lower end of a plate 140 on the lever 108. A spring 142 connected at one end to the latch 138 and at its other end to a pin 144 on the lever 134 tends to hold the latch 138 in position to engage the plate 140. It will thus be evident that, when the slide 50 receives its forward movement the arm 108 is held back by the latch 138, so that the knife 104 does not move forwardly with the slide 50. The slide 50 carries an adjustable screw 146 which is ar-

ranged to engage and operate a finger 148 projecting from the latch 138. The forward movement of the slide 50, however, does not carry the screw 146 far enough to act on the finger 148 since it is necessary to allow time for the overlaying member to begin its upward movement after the slide 50 has arrived at the end of its forward movement. Release of the arm 108 is accordingly effected in response to a movement 10 of the lever 134 such as to cause the screw 146 to act on the finger 148 to disengage the latch 138 from the plate 140. This movement is effected early in the upward movement of the overlaying member by a path cam 150 formed in one 15 side of the cam wheel 68 on the shaft 70 and engaging a roll 154 on the lever 134. In the return of the parts to starting position the latch 138 is engaged by a stop shoulder 156 on the lever 134 to hold it in position to connect again with the plate 140 when the slide 50 arrives at the 20 end of its retractive movement.

In the operation of the machine briefly summarized the operator presents the shoe in engagement with the edge gage 28 and with the sole 25 rest 30 in position for the gripper jaws 40, when operated, to engage that portion of the upper upon which a lasting operation is to be performed and then starts the machine by depressing a starting treadle (not shown) with which the machine is provided. The gripper then grips the upper and pulls it heightwise of the last and inwardly over the insole. In pulling the upper inwardly over the insole the gripper is positioned substantially as indicated in Fig. 2. While the 30 gripper is thus holding the upper the overlaying member 42 is moved forwardly by the action of the cam 64 on the slide 50 and substantially at the beginning of its forward movement is swung downwardly by the rocking of the member 56 about the axis of the rock-shaft 60. As the overlaying member is swung downwardly it engages the end of the adhesive tape and presses it against the upper while also pressing the upper down upon the bottom face of the insole at the edge of the shoe bottom. The overlaying member is then 35 moved inwardly in a plane substantially parallel to the bottom surface of the last to press the margin of the upper progressively against the bottom face of the insole in position to adhere thereto through the action of the cement, and as the overlaying member moves inwardly it feeds a length of tape from the roll 80 and applies it to the margin of the upper and to the adjacent portion of the insole to hold the upper in lasted 40 position (Fig. 3). As the slide 50 moves forwardly the knife 104 is retracted against the action of the latch 138 upon the arm 108.

After the slide 50 has completed its forward 45 movement the cam 76 acts to swing the lever 72 and the member 56 in a counterclockwise direction as viewed in Fig. 1 about the axis of the shaft 60 to move the overlaying member upwardly away from the shoe bottom. In predetermined time relation to the upward movement 50 of the overlaying member and preferably at or near the time when the overlaying member arrives in the position shown in Fig. 4 the arm 108 is released by the latch 138 to the action of the spring 114 in response to movement of the lever 134, and the knife 104 is thereby rendered operative to sever the fastening 75 of adhesive material from its source of supply. After the temporary fastening has been severed from the roll of fastening material the slide 50 is retracted to its 55

starting position along with the other operating parts of the machine, the plate 140 on the arm 108 being carried by this movement into position for the latch 138 to engage it.

By reference to Fig. 6 it will be seen that the 5 fastenings are applied in closely adjacent positions along the sides of the shoe from substantially the heel-breast line forwardly to the toe end of the shoe. It will be evident that the fastenings are applied in directions substantially 10 normal to the edge curvature of the insole and that they may overlap one another to some extent particularly along the ball portions, and in narrow shank shoes, along the shank portion without this affecting their holding power. 15

After the side-lasting operation has been performed the ends of the shoe are lasted in the usual manner, after which the shoe is in condition for the attachment of its outsole. As previously pointed out, the present invention contemplates 20 that if, for example, the outsole is to be fastened to the shoe by cement the temporary fastenings will preferably be removed from the shoe after the cement which has been applied to the 25 margins of the shoe upper materials or to the margin of the insole or to both, has set sufficiently to retain the upper in lasted position. This may be done conveniently without loss of time to the operator in a subsequent operation on the shoe, for example when the overlasted margin of the 30 upper is roughened to prepare it for the reception of adhesive for securing it to an outsole.

The overlasted margin of the upper is usually roughened by means of a roughening tool such as that indicated at 160 in Fig. 7 which is rotated 35 in a direction for its shoe-engaging portion to move inwardly from the edge of the shoe bottom. A suitable tool, such as is customarily employed for the purpose, is disclosed and claimed in Letters Patent of the United States No. 1,989,078, 40 Granted January 29, 1935, upon an application of Charles G. Brostrom. Roughening tools of the type disclosed in the above-mentioned application are each provided with a plurality of wire bristles which act to roughen the upper without 45 tearing or otherwise damaging it, and as the shoe herein shown is moved progressively past the roughening tool to cause the tool to act from substantially the heel breast line forwardly to the toe end of the shoe the wire bristles engage 50 and remove the strips 75 of adhesive material from the overlaid margin of the upper, the shoe being preferably moved relatively to the tool to remove also any portions of the strips adhering 55 to the insole.

After the overlaid margin of the upper has been roughened and the temporary fastenings removed from the shoe an outsole may be secured to the upper by an adhesive in the usual manner, 60 a heel assembled on and secured to the shoe and certain finishing operations performed to prepare the shoe for the market.

Having thus described my invention what I claim as new and desire to secure by Letters 65 Patent of the United States is:

1. In a lasting machine, a member for laying the margin of an upper over an insole on a last, and means for moving said member inwardly over the insole, said member being arranged to 70 apply to the upper and the insole an adhesive fastening to hold the upper in lasted position.

2. In a lasting machine, means movable to lay the margin of an upper inwardly over an insole successively in different locations along the edge 75

of the shoe bottom, said means being constructed and arranged to apply an adhesive fastening to the upper and the insole in operating on the shoe in each location.

5. In a lasting machine, means for positioning an upper in lasted relation to an insole on a last and for fastening it in lasted position, said means comprising mechanism movable inwardly over the shoe bottom to lay the margin of the upper over the insole and also to apply a fastening of adhesive material in position to adhere to the upper and the insole.

6. In a lasting machine, the combination with means for pulling an upper over a last, of an overlaying member movable to press the margin of the upper into position to adhere to an insole on the last through the action of cement and also to lay a strip of adhesive material over the margin of the upper and against the bottom face of the insole to hold the upper in lasted position.

7. In a lasting machine, the combination with means for pulling an upper over a last, of a member movable inwardly over the shoe bottom for applying rolling pressure to the margin of the upper to lay it into position to adhere to an insole on the last through the action of cement, said member being arranged to act during its inward movement to apply a strip of adhesive material to the upper and the insole to fasten the upper in lasted position.

8. In a lasting machine, the combination with means for pulling an upper over a last, of means for laying the margin of the tensioned upper over an insole on the last and for feeding from a source of supply a fastening of adhesive material and pressing it into position to adhere to the upper and the insole.

9. In a lasting machine, the combination with means for pulling an upper over a last, of means for positioning the upper in lasted relation to an insole on the last and for fastening it in lasted position comprising a member movable to lay the margin of the upper over the insole and also to apply a strip of adhesive material to the upper and insole, and means for severing said strip from a source of supply.

10. In a lasting machine, means for positioning an upper in lasted relation to an insole on a last and for fastening it in lasted position comprising a member movable to lay the margin of the upper over the insole and also to feed a strip of adhesive material from a roll of such material and to press it upon the upper and insole, and means for severing the strip from the roll of material.

11. In a lasting machine, the combination with means for pulling an upper over a last, of means for positioning the upper in lasted relation to an insole on the last and for fastening it in lasted position comprising a freely rotatable roll movable inwardly over the shoe bottom to lay the margin of the upper against the insole and to apply a strip of adhesive material to the upper and insole, and a member movable with said roll and arranged to bend the adhesive material about the roll in position to be applied to the shoe by the roll.

12. In a lasting machine, the combination with means for pulling an upper over a last and inwardly over an insole on the last, of means for engaging the end of a roll of adhesive material and for pressing it into position to adhere to said margin and for thereafter feeding a length of the adhesive material from the roll and laying it over the margin of the upper while pressing

said margin into position to adhere to the bottom face of the insole, said means being movable inwardly over the insole beyond the edge of the upper to lay the adhesive material against the insole, and means for severing the applied portion of the adhesive material from the roll.

13. In a lasting machine, the combination with a gripper for pulling an upper over a last, of an overlaying member for laying the margin of the upper over an insole on the last, said member being arranged to engage the end of a roll of adhesive material and to feed from the roll a portion of it and apply it in position to adhere to the upper and the insole, and means for severing the applied portion of adhesive material from the roll.

14. In a lasting machine, the combination with a gripper for pulling an upper over a last, of an overlaying member movable inwardly over the shoe bottom to lay the margin of the tensioned upper over an insole on the last, a member for supporting the end of a roll of adhesive material in position to be engaged by said overlaying member to cause a portion of the adhesive material to be laid over the margin of the upper and against the bottom face of the insole by the overlaying member during its inward movement, and means for severing from the roll of adhesive material that portion of it which has been applied to the upper and the insole.

15. In a lasting machine, the combination with means for pulling an upper over a last, of an overlaying roll movable toward the bottom face of an insole on the last into position to press the margin of the tensioned upper against the outer edge portion of the bottom face of the insole and then inwardly over the shoe bottom in a plane substantially parallel to the bottom surface of the last to lay the margin of the upper throughout its entire width into position to adhere to the bottom face of the insole.

16. In a lasting machine, the combination with means for pulling an upper over a last, of a member for laying the margin of the upper in lasted relation to an insole on the last, means constructed to impart to said member a movement toward the shoe bottom in a direction inclined toward the bottom face of the insole, and additional means for swinging said member into position to press the margin of the upper against the outer edge portion of the bottom face of the insole substantially at the beginning of its movement over the shoe and for thereafter controlling the movement of said member so as to cause it to move over the shoe bottom in a plane substantially parallel to the shoe bottom.

17. In a lasting machine, the combination with means for pulling an upper over a last, of an overlaying member for applying pressure to the margin of the tensioned upper to lay it in position to adhere to an insole on the last, means for moving the overlaying member toward the bottom of the shoe in a direction inclined toward the bottom face of the insole, and means for imparting to said member substantially at the beginning of its inclined movement a movement in a different direction to carry it into position to press the margin of the upper against the bottom face of the insole in a location substantially at the edge of the insole.

18. In a lasting machine, the combination with means for pulling an upper over a last, of an overlaying member for pressing the margin of the tensioned upper into position to adhere to an insole on the last, a carrier for moving the over-

laying member inwardly over the bottom of the shoe, a pivoted support for the carrier relatively to which the carrier is movable in a direction inclined toward the bottom face of the insole, and means constructed to operate in time relation to the movement of the carrier to swing the support about its pivot and thus to move the overlaying member into position to press the margin of the upper against the outer edge portion of the bottom face of the insole substantially at the beginning of its inward movement over the shoe bottom.

17. In a lasting machine, a member for laying the marginal portion of an upper inwardly over an insole on a last, a carrier supporting said member and movable in a forwardly and downwardly inclined direction to impart to the member its operative movement, and means for imparting to said carrier also a downward swinging movement to cause the overlaying member to press the upper against the outer edge portion of the bottom face of the insole prior to its movement farther inwardly over the insole.

18. In a lasting machine, a member for laying the marginal portion of an upper inwardly over an insole on a last, a carrier supporting said member and movable in a forwardly and downwardly inclined direction to impart to the member its operative movement, means for thus moving said carrier, and additional means for swinging the carrier downwardly to cause the overlaying member to press the upper initially against the outer edge portion of the bottom face of the insole and for thereafter swinging the carrier upwardly during its movement to carry the member farther inwardly over the insole.

19. A lasting machine having, in combination, a gripper for pulling an upper over a last, a roll for overlaying the margin of the upper pulled by the gripper, a carrier for said roll movable toward and from the work, a pivoted support for said carrier relatively to which the carrier is movable in a direction inclined toward the bottom of the shoe, and automatic means for varying the direction of movement of said carrier by movement of the support about its pivot to cause the roll to be moved first into position to press the upper against the outer edge portion of the bottom face of an insole on the last and then to be moved inwardly over the shoe bottom in a plane substantially parallel to the bottom surface of the last to lay the margin of the upper against the insole.

20. A lasting machine having, in combination, a gripper for pulling an upper over a last, an overlaying member, a carrier for said overlaying member movable toward and from the work, a pivoted support for said carrier relatively to which the carrier is movable in a direction inclined toward the bottom of the shoe, means for moving the carrier relatively to its support, and cam-controlled means for swinging the support about its pivot to vary the direction of movement of the carrier and thus to cause the overlaying member to be moved into position to press the margin of the upper against the bottom face of the insole adjacent its outer edge and then to be moved inwardly over the shoe bottom in a plane substantially parallel to the bottom surface of the last to lay the margin of the upper against the insole.

21. A lasting machine having, in combination, a gripper for pulling an upper over a last, an overlaying member, a tape-controlling member adjustable toward and from said overlaying

member and having an end portion formed and arranged to bend an adhesive tape beneath said overlaying member, and means for moving said overlaying member inwardly over the shoe bottom to press the margin of the upper against the bottom face of an insole on the last and to lay said adhesive tape over the margin of the upper and against the bottom face of the insole to hold the upper in lasted position.

22. A lasting machine having, in combination, a gripper for pulling an upper over a last, an overlaying member, a member for supporting the end of a roll of adhesive material beneath said overlaying member, means for moving the overlaying member inwardly over the shoe bottom to lay the margin of the upper against an insole on the last and to apply a length of the adhesive material in position to adhere to the upper and the insole, and means for severing from the roll of adhesive material the applied portion of it after the overlaying member has completed its inward movement.

23. A lasting machine having, in combination, a gripper for pulling an upper over a last, an overlaying member, a member for supporting the end of a roll of adhesive material beneath said overlaying member, means for moving said overlaying member inwardly over the shoe bottom to lay the margin of the upper against an insole on the last and to feed from said roll of adhesive material a portion of it and lay it over the upper and against the insole, a knife for severing the applied portion of the adhesive material from the roll, and means for operating the knife after the overlaying member has completed its inward movement.

24. A lasting machine having, in combination, a gripper for pulling an upper over a last and inwardly over an insole on the last, an overlaying member, a member arranged to cooperate with said overlaying member to bend the end portion of a roll of adhesive tape around said overlaying member, means for moving said overlaying member into position to force the margin of the upper against the insole and to press the end of the tape against the margin of the upper, said means being constructed and arranged to impart to said overlaying member a movement inwardly over the shoe bottom to press the margin of the upper against the insole and to lay the tape over the upper and against the insole, and means constructed and arranged to operate in time relation to the movements of the overlaying member to sever the applied portion of the tape from the roll after the overlaying member has completed its inward movement.

25. In a lasting machine, the combination with a gripper for pulling an upper over a last, of an overlaying member movable inwardly over the shoe bottom to press the margin of the tensioned upper into position to adhere to an insole on the last and also to feed from a roll of adhesive tape a portion of it and lay it over the upper and against the insole, a knife for severing from the roll of tape the applied portion of it, means for operating the knife comprising a spring arranged to be tensioned by the movement of the overlaying member inwardly over the shoe bottom, and mechanism for releasing said spring to render it operative after the overlaying member has completed its inward movement.

26. In a lasting machine, the combination with a gripper for pulling an upper over a last, of an overlaying member movable inwardly over the bottom of the shoe for pressing the margin of

the upper against an insole on the last, a member arranged to cooperate with said overlaying member to position the end of a roll of adhesive material between said overlaying member and the shoe 5 and thereby to cause said overlaying member during its inward movement to feed from said roll a length of adhesive material and lay it over the upper and the insole, means for moving the overlaying member inwardly over the shoe bottom, a 10 knife arranged to sever from the roll of adhesive material that portion of it applied to the upper and the insole, a spring for operating said knife, means for tensioning said spring by the movement of the overlaying member inwardly over the shoe 15 bottom, and means constructed and arranged to operate independently of said movement of the overlaying member after the completion of said movement to release the spring for the operation of the knife.

20 27. In a lasting machine, the combination with means for pulling an upper over a last, of an overlaying member, a member for positioning the end of a roll of adhesive material beneath said overlaying member, means for moving said overlaying member inwardly over the shoe bottom to press the margin of the upper into position to adhere to an insole on the last and to lay the adhesive material over the upper and against the insole, means for imparting to said overlaying member 25 at the end of its inward movement a movement in a direction substantially at right angles to the direction of its inward movement to carry it away from the shoe bottom, and means constructed to operate in time relation to the movements of said overlaying member to sever from the roll of adhesive material the applied portion of it after the overlaying member has completed its movement inwardly over the shoe bottom and substantially at the time when the overlaying member begins its movement away from the shoe 30 bottom.

28. A lasting machine having, in combination, means for pulling an upper over a last, an overlaying member, a carrier for said overlaying member movable toward and from the work, a support on said carrier for a roll of adhesive tape, a member mounted on said carrier and arranged to cooperate with said overlaying member to position the end of the tape beneath the overlaying member, means for operating the carrier to move the overlaying member inwardly over the shoe bottom to press the margin of the upper against an insole on the last and to lay the tape over the upper and against the insole, a knife for severing the applied portion of tape from the roll, an arm pivotally mounted on said carrier for operating the knife, a spring for operating said arm, means for holding back said arm when the carrier moves toward the work and for thereby tensioning said spring, and means for releasing said arm after the carrier has completed its movement toward the work.

29. A lasting machine having, in combination, means for pulling an upper over a last, an overlaying member, a member arranged to cooperate with said overlaying member to support the end of a roll of adhesive material beneath said member, means comprising a carrier for imparting to said overlaying member movement heightwise of the shoe to press the margin of the upper against the outer edge portion of the bottom face of an insole on the last and to press the end of the adhesive material against the margin of the upper, then a movement inwardly over the shoe

bottom in a plane substantially parallel to the bottom surface of the last to lay the margin of the upper against the insole and to feed a portion of the adhesive material from the roll and to press it into position to adhere to the upper and the insole, followed by a movement upwardly away from the shoe bottom in a direction substantially at right angles to the direction of its inward movement, and a knife movable relatively to said overlaying member for severing the applied portion of the adhesive material from the roll substantially at the beginning of the upward movement of the overlaying member.

30. That improvement in methods of making shoes in which cement is used to secure the uppers in lasted relation to insoles which comprises assembling a shoe upper and an insole on a last, working the upper into lasted relation to the last and laying its margin inwardly over the insole with cement between the upper and the insole, fastening the upper in lasted position by fastening means which is adhesively secured to the upper and the insole in the overlaying operation, and after the cement has set sufficiently to retain the upper in lasted position removing the fastening means.

31. That improvement in methods of making shoes in which cement is used to secure the uppers in lasted relation to insoles which comprises assembling a shoe upper and an insole on a last, working different portions of the upper successively into lasted relation to the insole with cement between the upper and the insole, applying to each portion of the upper while working it into lasted position a fastening which is adhesively secured to the margin of the upper and then to the bottom face of the insole to hold the upper in lasted position, and after the cement has set sufficiently to hold the upper in lasted position removing the fastenings or at least those portions of them adhering to the margin of the upper.

32. That improvement in methods of making shoes in which cement is used to secure the uppers in lasted relation to insoles which comprises assembling a shoe upper and an insole on a last, working the upper into lasted relation to the last and insole with cement between the upper and the insole, fastening the upper in lasted position by fastening means which is adhesively secured to the upper and the insole, and thereafter roughening the overlasted margin of the upper and in the roughening operation removing the fastening means.

33. That improvement in methods of making shoes in which cement is used to secure the uppers in lasted relation to insoles which comprises assembling a shoe upper and an insole on a last, working different portions of the upper successively along the sides of the shoe into lasted relation to the last and insole with cement between the upper and the insole, fastening each portion of the upper in lasted position by a fastening which is adhesively secured to the margin of the upper and the bottom face of the insole, allowing the fastenings to remain on the shoe until the cement has set sufficiently to hold the upper in lasted position, and thereafter roughening the overlasted margin of the upper and in the roughening operation removing the fastenings.

34. That improvement in methods of making shoes in which cement is used to secure the uppers in lasted relation to insoles which comprises assembling a shoe upper and an insole on a last, pulling different portions of the upper successive-

ly along the sides of the shoe over the last and inwardly over the margin of the insole, pressing the margin of each pulled-over portion of the upper against the bottom face of the insole with cement between the upper and the insole and, 5 while pressing the upper against the insole, fastening it temporarily in lasted position by securing to its outer face and to the bottom face of the insole a strip of adhesive material, allowing the strips of adhesive material to remain on 10 the shoe until after the cement has set sufficient- ly to hold the upper in lasted position, and then removing the strips of adhesive material.

35. That improvement in methods of making 15 shoes which comprises assembling a shoe upper and an insole on a last, applying an adhesive to the marginal portions of the shoe upper materials, working a portion of the upper into lasted relation to the last and insole and fastening it 20 temporarily in lasted position by a fastening which is adhesively secured to the upper and the insole, similarly working other portions of the upper into lasted position and fastening them along the sides of the shoe, lasting the toe and heel portions of the upper, and thereafter roughening the overlasted margin of the upper and 25 removing the temporary fastenings.

36. That improvement in methods of making 30 shoes which consists in assembling a shoe upper and an insole on a last, applying cement to the marginal portions of the shoe upper materials, pulling different portions of the upper along the sides of the shoe over the last, laying the margin of each tensioned portion of the upper inwardly 35 over the bottom face of the insole and pressing it into position to adhere thereto, fastening each overlaid portion temporarily in lasted position by a strip of adhesive tape which is secured to the overlaid margin of the upper and to the bottom 40 face of the insole, lasting the toe and heel portions of the shoe while the upper at the sides of the shoe is held in lasted position by the strips of adhesive tape, and thereafter roughening the overlaid margin of the upper and in the roughening 45 operation removing the strips of adhesive tape.

37. That improvement in methods of making 50 shoes which comprises conforming a shoe upper to the contour of a last and laying the margin of the upper progressively from the edge of the shoe bottom inwardly over an insole on the last, and

progressively applying an adhesive fastening to the margin of the upper from the edge of the shoe bottom inwardly in the overlaying operation and pressing a portion of the fastening into position to adhere to the insole. 5

38. That improvement in methods of making 10 shoes which comprises assembling a shoe upper and an insole on a last, pulling the upper over the last, laying the margin of the upper from the edge of the shoe bottom inwardly over the bottom face of the insole, and while laying the upper over the insole progressively applying a strip of adhesive tape to the margin of the upper and then pressing the tape into position to adhere to the insole. 15

39. That improvement in methods of making 20 shoes which comprises conforming a shoe upper to the contour of a last and laying the margin of the upper from the edge of the shoe bottom inwardly over an insole on the last, engaging the 25 end of a roll of adhesive material and applying the adhesive material progressively to the margin of the upper in the overlaying operation, pressing a portion of the adhesive material against the insole, and severing from the roll the adhesive material applied to the upper and the insole.

40. That improvement in methods of making 30 shoes in which cement is used to secure the uppers in lasted relation to insoles which comprises assembling a shoe upper and an insole on a last, 35 working different portions of the upper into lasted relation to the last and insole with cement between the upper and the insole, fastening each overworked portion of the upper in lasted position by fastening means which is adhesively secured to the upper and the insole, and thereafter roughening the overlasted margin of the upper. 40

41. That improvement in methods of making 45 shoes which comprises assembling a shoe upper and an insole on a last, applying an adhesive to the marginal portions of the shoe upper materials, working a portion of the upper into lasted relation to the last and insole and fastening it in lasted position by a fastening which is adhesively secured to the upper and the insole, similarly working other portions of the upper into lasted position and fastening them along the sides of the shoe, lasting the toe and heel portions of the upper, and thereafter roughening the overlasted margin 50 of the upper. 50

LESTER S. MACDONALD.
